Francis Van Senus
INVENTOR
BY *Victor J. Evans*
ATTORNEY

UNITED STATES PATENT OFFICE.

FRANCIS VAN SENUS, OF MOLINE, ILLINOIS.

MATCH-BOX HOLDER.

1,381,522.

Specification of Letters Patent. Patented June 14, 1921.

Application filed May 22, 1920. Serial No. 383,425.

To all whom it may concern:

Be it known that I, FRANCIS VAN SENUS, a citizen of the United States, residing at Moline, in the county of Rock Island and State of Illinois, have invented new and useful Improvements in Match-Box Holders; of which the following is a specification.

- This invention relates to a holder for match boxes, the principal object of the invention being to provide a metal holder for holding the box so as to prevent the box from being broken when carried in the pocket.
- Another object of the invention is to provide means for projecting the match receptacle from the holder when a latch member on the holder is released in order to permit a match to be drawn from the receptacle.
- This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:—

Figure 1 is a perspective view of the holder with the box therein.

Fig. 2 is a longitudinal sectional view 35 through Fig. 1.

Fig. 3 is a detail view of the latch member.

In these drawings 1 indicates a holder made of metal or like material and having both of its ends open. A flange 2 is formed around one open end to hold the plate 3 which is loosely arranged in the holder. A smaller flanged plate 4 is connected to plate 3 by the springs 5. The ordinary penny match box 6 is placed in said holder, with its end abutting the plate 4. This box is held within the holder by the latch bar 7

which is hinged at one end to one side of the holder and its other end is detachably secured to the other side of the holder by any suitable form of fastener, as shown at 8. 50 The sides of the holder may be provided with openings for exposing the match striking surface of the sides of the box.

From the above it will be apparent that when the match box is inserted in the holder 55 and the bar 7 moved to closed position the end of the box engaging plate 4 will force the same against the plate 3 and thus compress spring 5. When bar 7 is moved outwardly said spring will expand and project 60 the box so that a match may be taken therefrom.

By this invention the matches may be carried in the pocket without danger of breaking the box and the receptacle containing 65 the matches will be automatically moved into a position to permit the matches to be removed therefrom as soon as the latch bar is swung into open position.

It is thought from the foregoing description that the advantages and novel features 70 of my invention will be readily apparent.

I desire it to be understood that I may make changes in the construction and in the combination and arrangement of the several 75 parts, provided that such changes fall within the scope of the appended claim.

What I claim is:—

A match box holder comprising a casing having its ends open and one end having an 80 inwardly extending flange, an end plate engaging said flange for closing the opening, a smaller plate having right angular flanges thereon for engaging the first plate, a spring connecting the two plates together, a latch 85 bar hinged at one end to said box and fastening means for connecting the other end of the bar to the other side of the box with the bar extending across the open end of the holder for holding the match box therein. 90

In testimony whereof I affix my signature.
FRANCIS VAN SENUS.
